UNITED STATES PATENT OFFICE.

STEPHEN D. HUNTER, OF PHILADELPHIA, PENNSYLVANIA.

AUTOMOBILE WIND-SHIELD.

No. 910,065.

Specification of Letters Patent.

Patented Jan. 19, 1909.

Application filed December 28, 1907. Serial No. 407,677.

To all whom it may concern:

Be it known that I, STEPHEN D. HUNTER, a citizen of the United States, residing at Philadelphia, county of Philadelphia and State of Pennsylvania, have invented a new and useful Improvement in Automobile Wind-Shields, of which the following is a full, clear, and exact description, reference being had to the accompanying drawings, which form a part of this specification.

The objects of my invention are; first, to so construct a two-part wind shield that the removable top part may be so secured to the stationary bottom part that the shield will be virtually as strong and durable as a unitary shield of equal height; secondly, to so construct the joint and securing devices, by means of which the two parts of the shield are to be secured, that the upper part may be attached to, and detached from, the lower part without the use of tools and without necessitating the employment of any detachable part of unwieldy size and length.

In the drawings: Figure 1 is a rear view, partly in section, of the wind shield supported from the dash board, the upper part being mounted in position above and upon the lower part. Fig. 2 is a longitudinal section through the abutting tubular supports, the mutually engaging plugs carried thereby, the frame-supporting brackets and the thumb-screw for holding the tubular supports in position after they are abutted and engaged. Fig. 3 is a partial side view showing the upper part of the shield dismounted and suspended at the side of the lower part.

a is the dash board of the motor vehicle. *b*, *b*, are the brass tubes supporting opposite ends of the lower frame *c* of the two-part wind shield.

d, *d*, are the brass tubes supporting opposite ends of the upper frame *e* of the wind shield.

The tubes *b* are supported from the dash board by means of brackets *f*. Each frame is secured to its two supporting tubes by means of straps *g*.

Into the upper end of each tube *b* is inserted a plug *h*. The upper end of the plug is provided with a frusto-conical end socket *i* whose upper end and widest diameter is substantially of the diameter of that of the plug, so that the annular upper end of the plug is reduced in thickness, preferably to

nearly or quite a knife edge. The plug *h* should be driven tightly into the tube *b* until the upper edge of the plug is approximately flush with the upper end of the tube.

Into the lower end of each tube *d* is inserted a plug *k*. The lower end of the plug is tapered to form a frusto-conical end *l* of approximately the shape and dimensions of the frusto-conical socket *i* formed in the upper end of the plug *h*. The plug *k* should be driven tightly into the tube *d* until the base of its tapered end is approximately flush with the lower end of the tube.

In the peripheral face of the wall of the tapered end *l* of the plug *k* is formed a V-shaped annular groove, having a wall *m* somewhat steeply inclined nearest the outer and lower end of the plug and a longer wall *n*, of slight inclination to the face of the end *l*, nearer the upper or inner end of the plug.

The strap *g* supporting the upper end of the lower tube *b* and its corresponding frame *c* has, in its thickened end wall, a screw-threaded orifice adapted to receive the shank of a thumb screw *o*. The tube *b* is provided with a similar threaded orifice alining with the threaded orifice in the bracket. The plug *h* is also provided with a similar threaded orifice in alinement with the orifice in the tube.

The threaded orifice in the plug *h* is located at such position that when the plug *h* is socketed in the plug *h*, the threaded orifice in the plug *h* will be immediately opposite the base of the groove *n*—*m*, or perhaps a little below the base of the groove, so that when the thumb-screw is threaded into the orifice in the bracket *g*, tube *b* and plug *h*, it will abut against the wall *m* of the groove and hold the plug *h* firmly in its socket and prevent its accidental displacement.

The mode of operation of the device will probably be clear from the foregoing description. Briefly, however, it may be said that to secure the upper frame to the lower frame, it is merely necessary to bring the tubes *d* over the tubes *b*, insert the plugs *k* into the plugs *h* and press or drive the upper tubes downwardly until the ends of the two tubes abut. The thumb-screw *o* is then screwed in until the rounded end thereof firmly engages the steep lower wall *m* of the groove in the tapered end *l* of the

plug *k*, thereby securely holding the plug *k* in its seat.

The following means are provided to sustain the upper frame alongside the lower frame when the former is dismounted (see Fig. 3). Secured to each tube *b*, at a distance below its top approximately equal to the length of a tube *d*, is a bracket *p*, which is provided with an upwardly-opening socket substantially corresponding in contour to the socket *i*. When the upper frame is dismounted, the plugs *k* of the tubes *d* are inserted into the sockets in the brackets *p*. Into the upper ends of the tubes *d* are inserted plugs *s* having conical sockets similar to sockets *i*. *r* is a yoke having at one end a frusto-conical projection *t* adapted to substantially fit the socket *i* in plug *h* and at the other end a frusto-conical projection *u* adapted to fit within the socket in plug *s*. When the tubes of the upper frame, after dismounting, are placed on the socketed brackets *p* as described, the yokes *r* are applied to the adjacent upper ends of the tubes *d* and *b* as shown. Thus the upper frame may be supported on and alongside the lower frame until it is desired to again mount the former upon the latter.

When the upper frame is mounted on the lower frame, the projections *t* of the yokes *r* may be inserted into the socketed brackets *p*, thereby supporting the yokes when not in use. The projections *t* of the yokes *r* are shown as provided with V-shaped grooves similar to groove *m-n* in the tapered end *l* of the plug *k*, the object being to enable the yoke to be securely held in place, if desired, by means of a thumb screw similar to thumb screw *o*; but as a thumb screw in this connection is not absolutely essential, it has not been illustrated.

It is apparent that the above construction is a simple one, permitting the ready attachment of the upper frame to the lower frame, whether it is to be supported in its mounted or dismounted position, and its ready detachment, and that no tools are necessary in either the operation of attaching or detaching.

Having now fully described my invention, what I claim and desire to protect by Letters Patent is:

1. A wind shield for automobiles comprising a two-part frame and two pairs of tubes, between which the frames are respectively supported, two plugs secured respectively within each two abutting tubes of the two frames, one plug having a conically shaped end socket, and the other plug having a tapered end provided with a groove and adapted to seat in said socket, there being alining orifices in that part of the socketed plug forming the wall of the socket and in the tube containing said

socketed plug, and a screw adapted to engage said orifices and extend into said groove.

2. A wind shield for automobiles comprising a two-part frame and two pairs of tubes, between which the frames are respectively supported, two plugs secured respectively within each two abutting tubes of the two frames, one plug having a conically shaped end socket, and the other plug having a tapered end provided with a groove having one steep wall nearest the outer end of the plug and one wall of relatively slight inclination to the tapered face of the plug, there being alining orifices in that part of the socketed plug forming the wall of the socket and in the tube containing said socketed plug, and a screw adapted to engage said orifices and seat against the steeply inclined wall of the groove when the tapered plug is seated in said socket.

3. A wind shield for automobiles comprising a two-part frame and two pairs of tubes, between which the frames are respectively supported, two plugs secured respectively within each two abutting tubes of the two frames, one plug having a conically shaped end socket, and the other plug having a tapered end provided with a groove and adapted to seat in said socket, a strap engaging the tube carrying the socketed plug and engaging also the corresponding frame, and a screw adapted to extend through said strap and through the wall of the last named tube and through that part of the socketed plug forming the wall of the socket and enter said groove.

4. A wind shield for automobiles comprising a two-part frame and two pairs of tubes, between which the frames are respectively supported, two plugs secured respectively within each two abutting tubes of the two frames, one plug having a conically shaped end socket, and the other plug having a tapered end provided with a groove having one steep wall nearest the outer end of the plug and one wall of relatively slight inclination to the tapered face of the plug, a strap engaging the tube carrying the socketed plug and engaging also the corresponding frame, and a screw adapted to extend through a threaded orifice in the strap and also through the wall of the last named tube and through that part of the socketed plug forming the wall of the socket and abut against the steeply inclined wall of the groove when the tapered plug is seated in said socket.

5. A wind shield for automobiles comprising a two-part frame and two pairs of tubes, between which the frames are respectively supported, two plugs secured respectively within each two abutting tubes of the two frames, one plug having a tapered end extending beyond the abutting end of

its tube and the other plug, which is flush with the abutting end of its tube, having a conically shaped end socket, and a screw extending through the wall of the last named 5 tube and through that part of the last named plug forming the wall of the socket and seating within a groove formed in the tapered end of the first named plug.

6. A wind shield for automobiles comprising a two - part frame and two pairs of tubes, between which the frames are respectively supported, two plugs secured respectively within each two abutting tubes of the two frames, one plug having a tapered 15 end of frustro - conical form extending beyond the abutting end of its tube and the other plug, which is flush with the abutting end of its tube, having a socket shaped to fit the tapered end of the first plug, the 20 outer edge of the wall of the socket being tapered to substantially a knife edge, and a screw extending through said wall of the socket and seating against the outer inclined wall of a transverse groove formed in the 25 tapered end of the first plug.

7. A wind shield for automobiles comprising a two - part frame and two pairs of tubes, between which the frames are respectively supported, socketed plugs secured 30 in the upper ends of the tubes of the lower frame, complementary plugs secured to the lower ends of the tubes of the upper frame,

socketed brackets located alongside the lower tubes at a distance from their upper ends substantially equal to the length of the upper 35 tubes, and separable integral yokes, one end of each yoke adapted to engage the upper end of one of the tubes of a pair and the other end of said yoke adapted to engage the upper end of the other tube of said pair 40 or one of the socketed brackets.

8. A wind shield for automobiles comprising a two - part frame and two pairs of tubes, between which the frames are respectively supported, socketed plugs secured 45 in the upper ends of the tubes of the lower frame, complementary plugs secured in the lower ends of the tubes of the upper frame, socketed brackets located alongside the lower tubes and adapted to receive the last named 50 plugs, socketed plugs inserted in the upper ends of the upper tubes, and separable integral yokes, each having at opposite ends projections adapted to engage respectively the socketed plugs in adjacent upper and 55 lower tubes.

In testimony of which invention, I have hereunto set my hand, at Philadelphia, on this 18th day of December, 1907.

STEPHEN D. HUNTER.
